UNITED STATES PATENT OFFICE.

LEON SPIRO, OF EVERETT, WASHINGTON.

AUTOMATIC BALANCE FOR AEROPLANES.

1,074,659.

Specification of Letters Patent.

Patented Oct. 7, 1913.

Application filed June 25, 1912. Serial No. 705,795.

To all whom it may concern:

Be it known that I, LEON SPIRO, a citizen of the United States, residing at Everett, in the county of Snohomish and State of Washington, have invented certain new and useful improvements in Automatic Balances for Aeroplanes, of which the following is a specification, reference being had therein to the accompanying drawing.

10 This invention relates to flying machines, and has for its object the production of an efficient balancing mechanism whereby the machine may be quickly and efficiently righted through an automatic mechanism herein-
15 after described.

Another object of this invention is the production of an efficient clutch mechanism whereby an elevating propeller will be driven upon the ends of the machine, pro-
20 vided the machine should begin to tip.

With these and other objects in view, this invention consists of certain novel constructions, combinations, and arrangements of parts, as will be hereinafter fully described
25 and claimed.

In the drawings:—Figure 1 is a front view of the machine. Fig. 2 is a front view of the machine partly broken away. Fig. 3 is a top plan view of the machine partly
30 broken away. Fig. 4 is a central longitudinal section of the machine. Fig. 5 is a central longitudinal section of the clutch mechanism used in connection with the machine. Fig. 6 is a section taken on line 6—6 of
35 Fig. 3.

By referring to the drawings by numerals, it will be seen that the machine comprises a frame 1 which carries the usual controlling wheels 2, and this frame 1 carries at each
40 end a transversely extending beam 3. A supporting bracket 4 is also carried near each end of the frame, and upon the supporting bracket is mounted the main drive shaft 5. Auxiliary shaft supporting stand-
45 ards 6 are supported by the bottom plane 7 of the machine, and the shaft 5 carries near its center a plurality of spaced gears 8, which gears are loosely mounted on the shaft
5, and are provided with clutch collars 9,
50 and the gear wheels 8 at all times revolve with the driving gear 10. The driving gear 10 is driven by means of the motor 11, and upon the shaft 12, which carries the driving gear 10, is mounted a main driving pro-
55 peller 13. A clutch collar 14 is slidably

mounted upon the shaft 5 intermediate the gears 8, and is adapted to be alternately shifted to engage the clutch collars 9 formed upon the gears 8. The clutch collar 14 is controlled by means of an operating lever 15 which lever is pivotally secured to the lower plane 7, as indicated at 16. The lever 15 straddles the clutch collar 14, as indicated in Fig. 5, and is held in engagement therewith by means of a pin 17 which travels in the slots 18. The upper end of the lever 15 is connected to a pendulum lever 19, by means of a link 20. The pendulum lever 19 carries a pendulum weight 22 and this lever 19 is suspended from the top plane 23 by means of a hanger 24. It will be seen that as the machine tips toward one side, the weight 22 will cause the lever 25 to be thrown over toward the side to which the machine is tipping, and throw the clutch collar 14 into engagement with the clutch collar 9, and cause the gear wheel 8 to rotate.

A driving gear 25 is carried by the shaft 5 near each end, and these driving gears 25 mesh with the driving gears 26 carried by the vertical propeller shafts 27. These shafts 27 are braced by means of the braces 3 formed upon each end of the machine. A propeller blade 28 is carried by each vertical shaft 27, and it will be seen that as the shaft 5 rotates, the propellers 28 will be in turn rotated. A clutch collar 14 is keyed to the shaft 5, although, of course, the lever 15 is loosely connected thereto, so that the collar 14 may revolve with the shaft 5. The clutch collar 14 is provided with a socket 29 near each end, in which is mounted a spring 30. This spring 30 is held within the socket by means of a collar 31, which collar is fixedly secured to the shaft 5 by means of a pin 32. It will, therefore, be seen that as soon as the weight 22 resumes its normal position, the spring 30 will force the clutch collar 14 out of engagement with the clutch 9 carried by the gear 8.

From the foregoing description it will be seen that a very efficient device has been produced which will cause the propellers upon each end of the machine to be operated so as to draw that end of the machine upwardly in case the machine should tip endwise. Since an automatic control device has been produced, it will be seen that the operation thereof will not have to depend upon

the skill of the operator to throw the device in an operative position in case of an emergency.

What is claimed is:—

- 5 A machine of the class described comprising a body comprising an upper and a lower plane, vertically extending bars holding said planes in spaced relation, a transversely extending bar secured to said vertically extending members, vertical shafts journaled within said transversely extending bar, a collar positioned upon each shaft and resting upon said transversely extending member for limiting the downward
- 10 movement of said shaft relative to said transversely extending bar, a propeller blade carried by the upper end of said shaft, a drive gear carried by the lower end of said
- 15

shaft, a drive shaft extending longitudinally of said lower plane, gears carried by 20 said shaft and meshing with said gears carried by said vertical shafts, a pendulum suspended from the upper plane, an arm carried by said pendulum and extending laterally thereof, a clutch operating lever secured 21 to said arm, and clutch means coöperating with said drive shaft and engaged by said clutch operating lever for driving said propellers carried by said vertical shafts as said pendulum is swung.

In testimony whereof I hereunto affix my signature in presence of two witnesses.

LEON SPIRO.
